THOMAS L. BRANNEN, OF BERLIN, NEW HAMPSHIRE.

PAPER CUTTING AND FOLDING MACHINE.

No. 893,136.

Specification of Letters Patent.

Patented July 14, 1908.

Application filed November 5, 1906. Serial No. 342,151.

To all whom it may concern:

Be it known that I, THOMAS L. BRANNEN, residing at Berlin, in the county of Coos and State of New Hampshire, have invented certain new and useful Improvements in Paper Cutting and Folding Machines, of which the following is a specification.

My invention relates to certain new and useful improvements in paper cutting and folding machines and it particularly seeks to provide a machine in which means are provided for cutting the paper and folding the same in one and the same machine.

Generically, my invention comprises a paper cutting and folding machine in which means are provided for feeding the paper to the cutter and means for receiving the paper from the cutter and folding the same and then transferring the folded paper out of the machine.

In its more detail nature my invention includes an improved mechanical adjustment for raising and lowering the folding devices so that sheets of different lengths may be folded either in the center or along any desired line.

My invention has for its object to provide means for operating the folding bar of the folding mechanism at predetermined times to allow the folding bar to remain inactive for a sufficient length of time to permit a sheet to be fed in alignment therewith and then operating the folding bar to pass the sheet between the folding rollers.

My invention also has for its object to provide an improved driving mechanism for the folding rollers, the feed rollers and the cutter mechanism, and also to provide an improved construction of folding roller mechanism, all of which will be first described in detail and then be specifically pointed out in the appended claims.

With other objects which will be readily understood by those skilled in the art to which the invention appertains, my invention also includes certain novel construction, combination and arrangement of parts, all of which will be first described in detail, and then be specifically pointed out in the appended claims and illustrated in the accompanying drawings, in which:

Figure 1, is a side elevation of my invention. Fig. 2, is a side elevation taken from the side opposite to that shown in Fig. 1. Fig. 3, is a top plan view of my machine,

parts being broken away. Fig. 4, is a vertical, longitudinal section of the machine taken substantially as the line 4—4 of Fig. 3. Fig. 5, is a detail view of the fixed knife holding frame. Fig. 6, is a detail elevation of one of the folding roller carrying frames. Fig. 7, is a detail view of the bearing for the folding roller shafts which co-operates with the frame shown in Fig. 6. Fig. 8, is a detail cross section on the line 8—8 of Fig. 4. Fig. 9, is a detail perspective view of the rotating knife cylinder, its co-operating fixed knife and guide and the supporting bearings therefor. Fig. 10, is a detail view showing the manner of adjustably mounting the carriages 13 on the supporting frame of the machine. Fig. 11, is a detail view of the bracket 36 herein-after referred to.

Referring now to the accompanying drawings in which like letters and numerals of reference indicate like parts in all of the figures, the main frame of the machine comprises the side standards 1—1 connected together by rods 1^a, as shown. The standards 1—1 carry extension frames 1^b which are secured thereto in any approved manner. At the rear end, the standards have brackets 1^c to support threaded shanks 2^a of bearing members 2, which have their shafts 2^a adjustable in the brackets 1^c by guides 2^b—2^c. Mounted in the bearing members 2 is a shaft 3 which has a bobbin 3^a upon which the roll of paper P is held, (see dotted lines in Fig. 4). The extension frame 1^b has bearings 4^x to receive the relatively fixed shafts 4—4^a of sets of cutter or trimming mechanism A and B, respectively. Adjustable bearings 5^x are also secured to the frame 1^b to receive the adjustable shafts 5—5^a of the cutter or trimming mechanism A and B. Each shaft 4—4^a carries rotatable knives 6—6^a respectively that are adjustable thereon by collars 6^b and 6^c respectively and set screws 6^d and 6^e respectively, while the shafts 5—5^a carry knives 7—7^a which overlap the knives 6—6^a respectively and are held in engagement therewith by adjustable collars 8—8^a and coil springs 9—9, as shown. Fixed guides bars 10—10^a co-operate with the respective sets of cutters A and B and are secured on the extension frame 1^b in any approved manner.

11 designates a drum on a shaft 11^a that is mounted in bearings 11^b on the frame 1^b, while a guard 12 co-operates with the drum 11 and is secured to the frame 1 by ears 12^a on

rods 12^b and screws or bolts 12^c passing through some of the ears 12^a and secured to the frame 1^b of the machine. (See Fig. 3).

Adjustably mounted on the main supporting frame 1 are carriages 13 having bearings 13^a and lugs 13^b for a purpose presently understood. The carriages 13 are secured in place by screw bolts 14 which pass through slots in the frame 1 to allow of limited longitudinal adjustment of the carriages 13 on the frame 1.

Mounted in the bearings 13^a of the carriages 13 is a shaft 15^a of the rotatable cylinder knife member 15 to which the relatively movable knife blade 16 is secured by screw bolts 16^a or in any approved manner.

18 designates the fixed knife carrying member which rests on the carriages 13 and is held parallel with the drum 11 and is also provided with a baffle or guide portion 18^a and slotted ends 18^b, through which ends the screw bolts 18^c pass to secure the member 18 to the carriages 13. A set screw 13^c passes through the lug 13^b and abuts the member 18 so that the fixed knife carrying member may be adjusted independently of the adjustment of the carriages 13 for a purpose presently to appear. The member 18 has a portion 18^d to which the fixed knife 19 is secured by screws 19^a, as shown. Secured to the member 18 at each side of the baffle portion 18^a thereof, is a spring metal arm 20 having a U-shaped bearing portion 20^a in which the ends of a shaft 21^a are mounted. The shaft 21^a carries a presser roller 21 whose surface is covered with strips 21^b of rubber or other suitable "non-slip" substance. The roller 21 lies parallel to the drum 11 and is held pressed thereagainst by the arms 20, (see Fig. 4).

40 The knife cylinder shaft 15^a carries a cam 15^b that coöperates with the heel 22^a of a rod 22 which is supported from one of the frame members 1—1^b by links 23 that are pivoted at 23^a to the frame and at 23^b to the rod 22, the pivot points 23^a of all the links 23 lying in straight alinement and parallel to the general longitudinal plane of the rod 22, while the pivot points 22^b of all the links lie also in straight alinement and parallel to the rod 22 so as to give the rod the proper movement, while still maintaining it always parallel to its first position, (see Fig. 4).

24—24 designate slideways secured to the frame members 1, which slideways are provided with grooves 24^a to receive the folding roller carrying frame members 25, one of which is shown in detail in Fig. 6, by reference to which it will be seen that each frame member 25 comprises a body portion having tongues 25^a to enter the slots 24^a of the slideways 24, as shown in Fig. 3. The frame members 25 are also provided with parallel vertical slots 25^b whose side walls are provided with tongues 25^c to enter grooves 26^a in bearing members 26 having shaft receiv-

ing bearing apertures 26^a as indicated, and one of which bearing members is shown in detail in Fig. 7. Each frame member 25 also includes a bearing portion 25^d and a screw receiving socket 25^e in which the supporting screw pillar 25^f is fixedly secured.) See Fig. 1.

25^g designates an arm formed with the body portion of the frames 25 whose lower end terminates in a bearing 25^h to receive the shaft 28 upon the ends of which the folder levers 29 are secured. Further reference to these levers 29 will be made later. Each frame 25 has attached thereto, an arm 27 having a slideway 27^a at right angles to the slots 25^b, which arm is secured to the body portion of the frame 25 by bolts 27^b or otherwise as may be found desirable. One of the levers 29 has a heel 29^a which abuts and coöperates with the rod 22 in a manner hereinafter more fully described. To the upper or free end of the levers 29 links 30 are pivotally connected at one end as at 30^a, see Figs. 1 and 5. The links 30 have their other ends pivotally connected at 30^b to the ends of the folding bar 31, the ends of which bar project beyond the links 30 into the slideways 27^a for a purpose presently made clear. Within each slot 25^b of the frames 25, a plurality of bearings 26 are held, preferably two in each slot, and the bearings 26 serve to receive the shafts 32^a of folding rollers 32 which are arranged in pairs, the rollers of each pair lying in horizontal planes and corresponding rollers of different pairs lying in parallel vertical planes. Around the upper pair of rollers 32 I pass an endless belt 33 of any approved material and I also pass an endless belt 34 around the lower pair of rollers 32 which belt also passes around a supplemental idler roller 35 on a shaft 35^a mounted in bearings 36^a of brackets 136 fastened to the frame of the machine. In practice, as shown in Fig. 4, the contacting faces of the belts 33 and 34 lie in a plane parallel with that containing the slideways 27^a of the arms 27, so that the folding bar 31 may be interposed between the rollers 32 that are adjacent to it at times to bring the paper sheet in between the rollers in its folded condition as will be more fully set forth hereafter. Each screw post or pillar 25^f of the frames 25 passes through a bearing aperture 36^a in the bracket 36 secured to the side frames 1 of the machine. The bracket 36 is also provided with a bearing aperture 36^b in a portion 36^b bent at right angles to that having the aperture for the screw pillar 25^f, to receive an adjusting shaft 37 on the ends of which beveled gears 37^a are secured which mesh with beveled gears 37^b on the screw posts 25^f, whereby when the shaft 37 is rotated, the motion thereof will be transmitted to the beveled gear 37^b and the frame 25 elevated or lowered according as the shaft 37 is rotated in one di-

rection or the other by means of a hand wheel 37^c shown most clearly in Fig. 4. The bracket 36 is shown in detail in Fig. 11. The shaft 28 carries a supplemental arm 28^x to the end of which a coil spring 28^y is secured, and the spring 28^y also is secured to one of the bracket members 25^e of the frame 25 so that the shaft 28 will rotate back to its normal position, when the heel 29^a is released from operative action with the rod 22, so as to withdraw the folding bar 31 from between the adjacent rollers 32, to permit a new sheet of paper to pass between the folding bar 31 and the rollers 32.

15 By referring now more particularly to Figs. 1 and 3, it will be seen that I mount a drive shaft 38 in bearings 38^a (see Fig. 4) on the frame 1, which drive shaft carries a fast pulley 39, and a loose pulley 40, together with a drive pinion 41 which meshes with a pinion 42 on a stub shaft 42^a secured to the frame 1^b of the machine, the pinion 42 in turn meshing with a master gear 43 on the shaft 11^a of the drum 11. The master wheel 43 meshes with a gear 44 on a stub shaft 44^a that is secured to the side frame 1^b and which in turn meshes with gears 45 and 46 arranged respectively on the shafts 4—4^a of the rotary trimming cutter mechanisms 30 A and B. The gears 45 and 46 mesh respectively with gears 47 and 48 on the shafts 5—5^a of the cutter mechanisms A and B respectively so that the proper motion may be imparted to the cutters 6—7, and 6^a 7^a, respectively.

The shaft 15^a of the knife cylinder 15 projects through one side of the machine and is held in the bearings 13^a of the slideways 13, as before stated, the projecting end of the 40 shaft 15^a however, carries a master gear 49 which meshes with a gear 50 on a stub shaft 50^a that is carried by an arm 50^b pivotally mounted on the shaft 15^a adjacent the gear 49 and which has a slotted arc portion 50^c terminating in a hand engaging member 50^d, and secured in place by a nut 51^a on a bolt 50^e secured to the frame 1 of the machine so that the arm 50^b may be adjusted on its fulcrum on the shaft 15^a to adjust the gear 50 to mesh with the pinion 52 on a shaft 52^a mounted in bearings on the frame of the machine and projecting through to the side opposite to that containing the pinion 52. The shaft 52^a on its opposite side carries a 55 belt pulley 53 having suitable belt tightening mechanism of any approved type, since the same *per se*, forms no part of my present invention, (see Fig. 2). The pulley 53 is belted with a second and similar pulley 54 on the drive shaft 38 before referred to.

In order to enable the proper adjustment of the folding rollers 32 and their proper intergearing and operative connection with the drive shaft, I provide a special construction of drive gear therefor and which

is most clearly illustrated in Fig. 2 of the drawings, by reference to which it will be seen that I provide the drum shaft 11^a at one end with a sprocket 55 around which an endless chain 56 passes. The chain 56 also passes around a sprocket 57 on a shaft 57^a that passes through the bearing portions 25^d of the frames 25 so as to be movable therewith. The sprocket chain 56 also passes around an idler pulley 58 on a stub shaft 58^a secured to the side frame of the machine and also around a second idler pulley 59 held on a shaft 59^a carried by an arm 59^b that is fulcrumed at its other end to the frame of the machine and is normally controlled by a spring 60 as shown to maintain the proper tension on the endless chain 56, it being understood that wherever I use the term "spring" in this specification, a weight may be used as the mechanical equivalent. The shaft 32^a of the lower pair of rollers 32 are each provided with gears 61 which mesh with a gear 62 on the shaft 57^a and the gear 61 of the roller 32 opposite that which is adjacent the folding bar 31 meshes with a gear 63 on the shaft 32^a of one of the rollers of the upper pair so that proper motion may be imparted to the belts 33 and 34 to make their coacting faces move accordingly.

So far as described the manner in which my invention operates will be best explained as follows. The roll of paper P is mounted on the bobbin 3^a and passes through either set of trimmers A and B, see dotted lines Fig. 4, and over the drum 11 and down between the knives 16 and 19, as shown. The paper is fed to the knives 16 and 19 by the drum 11 and presser roller 21 through the medium of the drive shaft 38 and its gear connections with the drum shaft 11^a. As motion is imparted to the drive shaft 38, the motion therein is transmitted through the gears, chain and belt mechanisms, so that the paper will be fed by the roller to the cylinder knife between it and the fixed knife 19, while the knife cylinder 15 will be rotated in the direction of the arrow to cut the paper as the knives reach the position shown in Fig. 4. As this operation takes place, it should be understood, a length of paper has passed down between the folding bar 31 and the adjacent rollers 32 as shown in dotted lines in Fig. 4, which length of paper is cut off by the knives 16 and 19 from the main strip and as the cam 15^b rests on the bar 22 it in turn through the coaction of the heel 29^a will move the lever 29 to force the folding bar 31 between the adjacent rollers 32, carrying with it the paper strip, that has been cut off by the knives 16 and 19. The rollers 32 and their belts 33 and 34 then take up the folded edge of the paper and at the same time, the cam 15^b releases the bar 22 which drops to its normal position, while the spring 130

28^y returns the lever 29 to its original position and withdraws the folding bar 31, thus allowing the belts 33 and 34 to continue the folded strip through the rollers 32 and along 5 past the roller 35 onto a suitable receiving table, not shown. By manipulating the hand wheel 37^c the frame 25 can be raised or lowered to so change its relative distance from the knife 19 that the paper can be 10 folded along any desired line in any desired proportion between certain limits and also paper of different lengths can be folded by this machine either centrally or in proportionate parts.

15 When it is desired to adjust the relatively fixed knife 19 into proper position with respect to the knife 16, it is only necessary to manipulate the set screws 13^c to adjust the member 18 after which it can be firmly 20 clamped into position by the securing bolts.

When it is desired to adjust the cutting mechanism back or forth in the supporting frame, it is only necessary to move the carriage 13 longitudinally by loosening the bolts 25 14, which longitudinal adjustment is only limited by the length of the slots through which the bolts 14 pass, thus allowing for the adjustment of the line of contact between the cutters 16 and 19 to allow it to be placed in 30 proper vertical alignment with the folding mechanisms so that as the folding bar 31 recedes from the rollers 32 the paper strips may be passed between the bar 31 and the rollers 32 to be engaged by the bar 31 as it is moved 35 toward the rollers 32 to force the paper between the rollers in its folded condition.

The cam 15^b and the bar 22 together with the coöperating connections with the folding bar 31 are so arranged that the cam will 40 operate the rod 22 at the proper time to give the proper throw to pass the folding bar 31 through between the first pair of folding rolls 32 and return it in proper time to allow the next sheet or sheets to pass between the 45 folding bar and the folding rollers.

It should be understood that all gearing between the various parts may be regulated and adjusted in their relative proportions to 50 perform the proper correlative movement of the various parts, as will be readily understood by those skilled in the art to which the invention appertains.

The belts 33 and 34 it might be mentioned, are preferably made of canvas, although they 55 may be formed of any other suitable material.

By arranging the rotating knife cylinder in back of the drum 11 and partly below the same and by rotating it as shown and described, the knife 19 brings the paper back into a position to properly coöperate with the folding bar.

While but one paper roll carrier has been shown on the machine in the drawings, yet 60 in practice, the paper rolls are supported in

separate frames, and several strips of paper are fed to the drum 11 and presser roll which coöperates therewith, thus enabling a plurality of strips to be trimmed, cut and folded at the same time.

Any number of the cutting mechanisms A and B may be provided, depending upon the number of sheets desired to be used, for instance, while each cutting mechanism A and B can trim sheets from several rolls simultaneously, yet their capacity is limited, and say if the paper is of such thickness that one of said trimmers A can cut but twelve strips of paper then the second set B will be used to cut twelve more, thus making it possible to 70 transversely cut twenty-four sheets feeding them all at the same time by the drum 11 and its presser roll.

As many supports for the paper rolls may be provided as may be found desirable in 80 practice.

From the foregoing description taken in connection with the accompanying drawings, it is thought the complete construction, operation and many advantages of my invention 90 will be readily understood by those skilled in the art to which the invention relates.

What I claim:—

1. In a machine of the class described, the combination with an adjustable cutting mechanism, of a folding mechanism, and means coöperatively connected with the cutting mechanism for operating the folding mechanism and means for adjusting the folding mechanism toward or from the cutting mechanism, substantially as shown and 95 described.

2. In a machine of the class described, the combination with an adjustable transverse strip cutting mechanism, of an adjustable folding mechanism, and means coöperatively connected with the cutting mechanism for operating the folding mechanism therefrom, substantially as shown and 105 described.

3. In a machine of the class described, a feed drum and a pressure roller coöperating therewith, a relatively fixed cutting knife and a rotatable cylinder knife coöperating therewith, supporting carriages for said fixed 115 knife and said rotatable cylinder knife combined with folding mechanism for receiving the cut strip and folding the same together with means for adjusting the fixed knife toward or from the rotatable cylinder knife, 120 substantially as shown and described.

4. In a machine of the class described, a feed drum and a pressure roller coöperating therewith, a relatively fixed cutting knife and a rotatable cylinder knife coöperating 125 therewith, supporting carriages for said fixed knife and said rotatable cylinder knife combined with a folding mechanism for receiving the cut strip and folding the same together with means for adjusting the fixed knife 130

toward or from the rotatable cylinder knife, and a drive shaft and means coöperatively connecting the feed drum, the rotatable cylinder knife and the folding mechanism 5 with said drive shaft so that the motion of the drive shaft will be imparted thereto, substantially as shown and described.

5. In a machine of the class described, a cutting mechanism comprising a relatively 10 fixed knife and a rotatable cylinder knife, combined with a folding mechanism, said folding mechanism comprising a plurality of pairs of belted folding rollers, a folding bar coöperating therewith, supporting frames 15 for said rollers and said folding bar, means coöperatively connected with said folding bar and said rotatable cylinder knife for operating the folding bar at predetermined times, means for rotating said rotatable 20 cylinder knife and said folding rollers, substantially as shown and described.

6. In a machine of the class described, a cutting mechanism comprising a relatively fixed knife and a rotatable cylinder knife, 25 combined with a folding mechanism, said folding mechanism comprising a plurality of pairs of belted folding rollers, a folding bar coöperating therewith, supporting frames for said rollers and said folding bar, means co- 30 operatively connected with said folding bar and said rotatable cylinder knife for operating the folding bar at predetermined times, means for rotating said rotatable cylinder knife and said folding rollers, and means for 35 adjusting the folding roller supporting frames toward or from the cutting mechanism.

7. In a machine of the class described, a cutting mechanism comprising a relatively 40 fixed knife and a rotatable cylinder knife, combined with a folding mechanism, said folding mechanism comprising a plurality of pairs of belted folding rollers, a folding bar coöperating therewith, supporting frames 45 for said rollers and said folding bar, means coöperatively connected with said folding bar and said rotatable cylinder knife for operating the folding bar at predetermined times, means for rotating said rotatable 50 cylinder knife and said folding rollers, means for adjusting the folding roller supporting frames toward or from the cutting mechanism, and said last named means comprising a rotatable adjustable shaft, a turn wheel 55 mounted thereon, a screw bolt carried by the supporting frames for the belted folding rollers and gear connections between said screw portions and said adjusting shaft.

8. In a machine of the class described, a 60 plurality of trimming and cutting mechanisms for trimming paper longitudinally, a feed drum and presser roller therefor, said paper adapted to pass over said feed drum, a second cutting mechanism for transversely 65 cutting the paper into sections, means for re-

ceiving said sections and folding the same, said folding means including a reciprocating folding bar, folding rollers coöperating therewith, and means for adjusting said folding rollers toward or from the second cutting 70 mechanism.

9. A cutting and folding mechanism for paper cutting and folding machines comprising a fixed knife carrying member, a knife fixedly secured thereto, supporting carriages 75 for said fixed knife carrying member, means for adjustably holding said fixed knife carrying member on said supporting carriages, a rotatable cylinder knife mounted in bearings in said carriages for coöperating with 80 said fixed knife, means for feeding paper to said knives, together with a folding mechanism for receiving the paper as it leaves said knives, and folding the same, substantially as shown and described. 85

10. In a machine of the class described, a transverse strip cutting mechanism, means for feeding the strip to the cutting mechanism, combined with a folding mechanism for receiving the cut sections of strip from the 90 cutting mechanism and folding the same, said folding mechanism comprising folding rollers and a reciprocating folding bar, means operated directly from the cutting mechanism for reciprocating the folding bar at pre- 95 determined times, and means for adjusting the folding bar and folding rollers simultaneously toward or from the cutting mechanism substantially as shown and described.

11. In a machine of the class described, a 100 strip cutting mechanism combined with a strip folding mechanism including folding rollers and a reciprocating folding bar, together with means for simultaneously adjusting the folding rollers and folding bar toward 105 or from the cutting mechanism, and means for adjusting the cutting mechanism at right angles to the direction of adjustment of the folding mechanism, substantially as shown and described. 110

12. In a machine of the class described, a paper feeding and a paper cutting mechanism, comprising a rotatable cutter and a fixed cutter, means for adjusting the fixed cutter toward or from the rotatable cutter, combined with a folding mechanism, means for adjusting the entire folding mechanism toward or from the cutting mechanism, and means for adjusting the entire cutting mechanism in a direction at right angles to the 120 adjustment of the folding mechanism, substantially as shown and described.

13. In a machine of the class described, a cutting mechanism combined with a folding mechanism, said folding mechanism comprising roller carrying frames, a reciprocating folding bar coöperating with said rollers, said roller carrying frames having guide-ways to receive said folding bar, means operable directly from the cutting mechanism for re- 125 130

ciprocating the folding bar at predetermined times, substantially as shown and described.

14. In a machine of the class described, a cutting mechanism combined with a folding mechanism, said folding mechanism comprising roller carrying frames, a reciprocating folding bar coöperating with said rollers, said roller carrying frames having guide-ways to receive said folding bar, means operable directly from the cutting mechanism for reciprocating the folding bar at predetermined times, and means for adjusting the roller carrying frames toward or from the cutting mechanism, substantially as shown and described.

15. In a machine of the class described, a cutting mechanism combined with a folding mechanism, said folding mechanism comprising roller carrying frames, a reciprocating folding bar coöperating with said rollers, said roller carrying frames having guide-ways to receive said folding bar, means operable directly from the cutting mechanism for reciprocating the folding bar at predetermined times, means for adjusting the roller carrying frames toward or from the cutting mechanism, substantially as shown and described.

mined times, means for adjusting the roller carrying frames toward or from the cutting mechanism, said roller carrying frames having their rollers arranged in sets, endless belts passing around each set, and an idler pulley around which one of said endless belts passes, substantially as shown and described.

16. In a machine of the class described, a plurality of trimming and cutting mechanisms for trimming paper longitudinally, a feed drum and presser roller therefor, said paper adapted to pass over said feed drum, a second cutting mechanism for transversely cutting the paper into sections, means for receiving said sections and folding the same, said folding means including a reciprocating folding bar, folding rollers coöperating therewith, and means for adjusting said folding rollers and said folding bar toward or from the second cutting mechanism.

THOMAS L. BRANNEN.
